(57) **CLAIM**

The ornamental design for a square rechargeable dc battery as shown and described.

DESCRIPTION

FIG. 1 is a perspective view of the square rechargeable dc battery;

FIG. 2 is a rear view of the square rechargeable dc battery; FIG. 3 is a bottom view of the square rechargeable dc battery;

FIG. 4 is a top view of the square rechargeable dc battery; FIG. 5 is a right side view of the square rechargeable dc battery;

FIG. 6 is a left side view of the square rechargeable dc battery

FIG. 7 is a front view of the square rechargeable dc battery

FIG. 8 is a perspective view of the second embodiment of the square rechargeable dc battery;

FIG. 9 is a rear view of the second embodiment of the square rechargeable dc battery;

FIG. 10 is a bottom view of the second embodiment of the square rechargeable dc battery;

FIG. 11 is a top view of the second embodiment of the square rechargeable dc battery;

FIG. 12 is a right side view of the second embodiment of the square rechargeable dc battery;

FIG. 13 is a left side view of the second embodiment of the square rechargeable dc battery; and,

FIG. 14 is front view of the second embodiment of the square rechargeable dc battery.

The broken lines in the drawings illustrate portions of the square rechargeable dc battery that form no part of the claimed design.
